CIGAR LIGHTER

Herbert G. Lehmann, Bridgeport, Conn., assignor
to Automatic Devices Corporation, Bridgeport,
Conn., a corporation of Connecticut

Application December 28, 1937, Serial No. 182,063

6 Claims. (Cl. 219—32)

This invention relates to cigar lighters and more particularly to lighters adapted to be mounted in the dashboards of automobiles.

In current lighters, means have been provided for opening the circuit to the heating element when the heating element has attained its predetermined heat. In some instances, however, where the thermostatic or heat-responsive switch is mounted in heat-receiving relation with the heating element on the igniting unit, the operation of the switch is impaired due to the fact that, after repeated usage, burnt tobacco and other oxidized scale is deposited on the outer surface of the heating element and prevents proper heat transfer to the heat-responsive switch.

Accordingly, the present invention provides a control unit for opening the circuit to the heating element in which an auxiliary heating element is mounted on the base and operates the heat-responsive means for the circuit for the heating element. With such a construction, the heating element, which serves to control the circuit, is not removed from the holder and subsequently is not likely to become dirty or have its heat-transferring properties impaired so that the lighter will always function faithfully.

It has been found that the auxiliary heating element can be of any desired shape, but, preferably, it is made similar to that mounted on the igniting unit. When these two heating elements are so similarly constructed, their properties are substantially identical and the auxiliary heating element will open the circuit when the heating element on the igniting unit has reached a corresponding temperature. Also, since the same manufacturing operations can be used to form many of the elements, a lower cost of manufacturing is achieved.

The unit is mounted on the holder for easy removal therefrom, since it has no permanent connections with the holder and igniting unit, and, therefore, does not require dismantling of the latter elements when it is to be replaced or removed. The heat-responsive means on the control unit also can be readily removed for replacement if necessary. Because the unit can be readily removed from the holding device, the user of the cigar lighter can obtain a large variety of operating relations which will produce the characteristics suited to his needs.

For example, the two heating elements can be connected in series or parallel circuits and the circuit closed upon movement of the igniting unit into energizing position. The heat-respon-

sive switch, in this case, will open the circuit upon being heated and, if the heating element is not removed from energizing position, will again automatically close the circuit upon cooling off.

5 Or, the user of the device can have the two heating elements connected in either series or parallel relation and have the control unit provided with a manually operable switch which will close the circuit when the igniting unit is in energizing position and which will be opened by the heat-responsive means when the heating element attains its predetermined temperature. In this case, however, the circuit will not be automatically made if the user of the device should fail to 10 remove it, but would remain open until the manually operable switch is actuated again.

The igniting unit, which is the same for all possible arrangements of the circuit, is provided with a lens at its outer end and with openings 20 at its inner end in light-receiving relation with the heating element so that, when the latter becomes incandescent, the lens will glow and indicate that the lighter is ready for use.

Other features and advantages of the invention 25 will be apparent from the specification, when taken in connection with the drawings, in which:

Figure 1 is a side view of the device with the igniting unit in inoperative position, the holder being in section.

30 Fig. 2 is a longitudinal sectional view of the holder and control means and part of the igniting unit.

Fig. 3 is a section of the device taken along line 3—3 of Fig. 2.

35 Fig. 4 is a diagrammatical showing of the two heating elements connected in series through the thermostatic switch.

Fig. 5 is a view similar to Fig. 2, with the auxiliary heating element connected in parallel with 40 the heating element on the igniting unit.

Fig. 6 is a longitudinal section of a holder and control device and part of the igniting unit forming another form of the invention in which the two heating elements are in parallel relation 45 and showing the manually controlled switch on the control unit.

Fig. 7 is a plan view of the control unit shown in Fig. 6.

Fig. 8 shows another form of the invention, partly in section, showing the auxiliary control means with the manually operable switch and the heating element arranged for series connection with the heating element on the igniting unit.

50 Fig. 9 shows diagrammatically the circuit for

the two heating elements when arranged in parallel.

According to the present invention, a tubular sheet metal holder 20 is threaded as at 21 at its open end and is provided with a plurality of outwardly extending tangs 22 lanced therefrom adjacent the threaded end. The holder is adapted to be placed in an aperture in a dashboard 23 or other support with the tangs 22 engaging the back thereof and a collar or escutcheon plate 24 is threaded on the open end of the holder and into engagement with the front of the dashboard to lock the holder in place thereon.

The holder is provided at its inner end with a transverse wall 25. A conducting stud 26, having a head 26a and a threaded end 26b, is mounted in a central aperture in the end wall and is insulated therefrom by an insulating washer 27 having a projecting neck 27a passing through the end wall and another insulating washer 28, as shown in Fig. 2.

A contact 29, having the ends thereof formed to provide hook-shaped latches 29a as shown in Fig. 2, is positioned in the holder so as to extend under the head of the stud and be clamped between the head and the insulating washer 27 by means of a nut 30, threaded on the projecting end of the stud and which also clamps the stud in place in the end wall of the holder.

The contact and stud are connected to a suitable source of energy by means of a lug 31 secured to a conductor 32 connected to the battery or the like. The lug is positioned on the stud and locked in place by a nut 33. The holder has an opening 34 formed therein adjacent the contact 29 for a purpose to be later explained.

An igniting unit 35 is formed by a tubular sleeve 36 of insulating material having a handle 37 formed integrally therewith, or otherwise secured thereto, at one end and having the other end formed with a reduced diameter, as indicated at 38. A conducting cap 39 of metal or other conducting material is secured to the reduced end of the igniting unit by having a projecting threaded sleeve 40 which is threaded into the bore of the sleeve 36 as shown in Fig. 2. The conducting cap is of the same diameter as the reduced end of the sleeve so as to be spaced from the walls of the holder.

A heating coil 43, preferably a helical coil of resistance wire, is adapted to be mounted on the end of the igniting unit. The heating coil is mounted with one end secured to a contact cup 44 and the other end secured to the slotted end of a central stud 45 which electrically connects the same to the conducting cap. As shown in Fig. 2, the central stud 45 clamps the contact cup and heating element to the conducting cap. The contact cup, however, is insulated from the stud and the conducting cap by means of insulation 46.

The conducting cap and contact may be provided with suitable apertures or openings 47 through which light from the heating element, when the latter is brought to incandescence for use, is transmitted through the hollow body of the igniting unit to a lens 48 mounted in the end of the handle to indicate to the user of the device that the heating element or coil has acquired the desired heat and is ready for use.

The igniting unit is adapted to be removably mounted in the holder which is provided with a holding tang 50 lanced inwardly of the holder and formed with a latch or hook 51 which is adapted to engage a rounded shoulder 36a

formed adjacent the reduced end of the igniting unit so as to hold the igniting unit in a normal or inoperative position. However, upon pressure being exerted on the handle on the igniting unit, it can be readily moved inwardly in the holder into a position in which the contact cup is engaged by the latched ends 29a of the contact 29 to close a circuit through the heating element.

According to the present invention, a control unit, indicated generally by 52, is adapted to be mounted on a plurality of lugs 53 lanced from the holder so as to project outwardly therefrom. The control unit comprises a support 54, provided adjacent its ends with downwardly projecting legs 55, adapted to engage the projecting lugs 53 on the holder and be movably secured thereto by screws 56. An auxiliary heating coil 58 is mounted on the support. The auxiliary heating element may be of any design. However, in the preferred form of the invention, the unit is made as a helical coil which is similar to the one connected to the igniting unit in size and shape so that the two coils will have substantially the same characteristics. The heating coil has one end secured to a contact cup 59 and the other end secured to the slotted end of a central stud 60. As shown in Fig. 2, the central stud 60 secures the heating element and contact cup to the support with the contact cup insulated therefrom by insulating washers 61. The support adjacent one end is provided with an aperture 64 in which is mounted a tubular bushing 65 of insulating material through which a bolt 66 is passed and an insulating washer 67 is positioned on the bolt adjacent the undersurface of the support. A contact 68 is mounted on the lower end of the bolt and is held against the washer 67 by a nut 69 which locks the bushing in place on the support. The contact 68, when in this position, will extend through the opening 34 in the holder and extend into the path of the conducting cap to engage the latter and make contact therewith when the igniting unit is moved to energized position. Clamped between the head 66a and the bushing 65 is a thermostatic element 70, preferably made of bimetallic material, extending transversely of the heating coil and normally in engagement with a contact 71 carried by the contact cup, as shown in Fig. 2.

With this arrangement of elements, when the igniting unit is positioned into energized position, the contact 68 engages the conducting cap 39 and completes the circuit through both of the heating elements, the circuit will be from the conductor 32, through the lugs 31, through the stud 26, contacts 29, contact cup 44, heating coil 43, central stud 45, to the conducting cap 39, through the contact 68, through the bimetallic strip 70, to the contact 71, through the contact cup 59, auxiliary heating coil 58, central stud 60, and to ground on the holder.

After the circuit is thus closed, both of the heating elements will become energized and the heat from the auxiliary heating element 58 will cause the bimetallic switch means 70 to flex and open the circuit, at the same time the lens will glow, due to the light rays emitting when the heating element has become incandescent to indicate to the user that the heating element is ready for use.

When the heating element has acquired its desired heat, the thermostatic switch will flex in the position shown in dotted lines in Fig. 2 and open the circuit, whereupon the igniting unit can be removed for use. Should the user of the

device fail to remove the igniting unit from the holder, the circuit will again close when the thermostat has cooled sufficiently to close the circuit.

From the above construction, it will be seen that the auxiliary heating element serves merely a control function and remains fixed on the housing. Since it is usually positioned behind the dashboard, it is not likely to become dirty and will more accurately control the heating of the heating element than when the controlling means is associated with the heating element which is continually removed from the holding device for use and which becomes oxidized and covered with particles of tobacco adhering thereto during use for lighting cigars and cigarettes. This construction provides an effective and practical control unit for the heating element of the igniting unit since it can be removed and replaced or repaired with the minimum of operations and without dismantling the igniting unit and holding device, because it has no wiring connections with the holding device, the sole connection being through the contact inserted through the hole in the holder. It is merely necessary to unscrew the four screws and lift the control unit from the holder. Also, the thermostat can be removed, should it become damaged or injured, and can be replaced without dismantling the entire control unit.

In the above form of the invention, the circuit, through the two heating elements, has been a series circuit, as shown diagrammatically in Fig. 4. However, if desired, the circuit can be arranged so that the two heating elements are in parallel, as shown diagrammatically in Fig. 9, thus reducing the effective resistance of the two heating coils so that current flow will be greater and the device will operate more rapidly. In this form of the invention, the holder and igniting unit are constructed in the manner set forth above. The control unit, however, is replaced by a unit comprising a support 75 which is secured to the lugs on the holder in the manner previously described.

An auxiliary heating coil 76 is mounted on the support by having one end secured to a contact cup 77 and the other end secured to a central stud 78 which, as shown in Fig. 5, clamps the auxiliary heating element and contact cup to the support. As noted in Fig. 5, the contact cup and central stud are insulated from the support by means of insulation 79.

The central stud for the auxiliary heating coil has one end of a conductor 91 secured thereto but insulated from the support. The other end of the conductor 91 is secured to the source of electrical energy. In the herein preferred form of the invention, this is done by connecting the conductor 91 by means of a contact lug 92 to the stud 26, which is connected to the source of energy.

Secured to one end of the support 75, adjacent the heating element, is an upwardly projecting stud 80. The stud may be secured to the support in any manner, but, in the preferred form, it is provided with a reduced portion 80a, which is inserted in an aperture 81 in the support and headed over to be locked thereto. The stud is provided with a bore 82, into which is threaded a screw 83 for securing a thermostat 84 to the end of the stud so as to be clamped between the head of the screw and the end of the stud and extend transversely of the heating element in heat-receiving relation therewith, and engage a

contact 85 which is adapted to be mounted in the aperture 86 in the support and be insulated therefrom by insulation 87. Secured to the lower end of the contact 85, to bear against insulation 87 so as to be insulated from the support, is an additional contact 89 which is locked thereto by a nut 90. The contact 89 extends through the opening 34 of the holder. A contact strip 93 is secured to the contact cup and extends through an aperture 94 in the support and into the holder through the aperture 34, and is in juxtaposition with the contact 89. As the igniting unit is moved into energizing position in the holder, it engages the contact strip 93 and moves it into engagement with the contact 89 so as to connect the two heating elements to ground through the thermostatic switch.

In this arrangement, it will be seen that both of the heating coils have one contact in engagement with the source of energy, and the other contact connected through the thermostatic switch to ground.

With these two forms of the invention, the circuit is automatically closed when the igniting unit is moved into energizing position. However, it may be desirable to provide a manual control for the device. With such a control, the igniting unit can be moved into a position for closing a circuit through the heating elements so that when the manually controlled switch is operated the circuit will be completed. While the manually controlled switch may be of any type, the herein preferred form is a toggle switch, to be more fully described.

35 In the form of the invention shown in Figs. 6 and 7, the switch is applied to the control unit having a parallel connection with the heating element on the igniting unit. In this form of the invention, the control unit is provided with a base 95, which is adapted to be secured to the lugs 53 of the holder in the manner previously described. The base has one end turned up to provide an upstanding wall 96. A heating coil 97 has one end secured to a contact cup 98 and the other end secured in the slotted end 99a of a central stud 99. The stud clamps the heating coil and contact cup to the support, as shown in Fig. 6, and is insulated from the support by insulation 100. A contact 104 is secured to the stud so as to be insulated from the support and extends through the aperture 34 in the holder so as to engage the cap 33 when the igniting unit is moved into energizing position. The contact cup is connected to the source of energy by means of a conductor 101 having a connector lug 102, on one end adapted to be secured to stud 26, and a connector 103, at the other end which is secured to the contact cup as by welding or other suitable means.

60 Mounted in the slotted extension 99a of the stud is a bimetallic thermostat 105. The thermostat is mounted so as to extend transversely of the heating element, having the ends thereof free for flexing movement upon the heating element being energized.

70 The switch, according to the present invention, comprises a U-shaped resilient member 107 secured to the upstanding wall 96 on the base 95 by rivets 108 or the like, with the arms of the U projecting outwardly therefrom, as shown in Fig. 7. A pair of contact-carrying arms 109 are pivoted to the ends of the U-shaped member at 110 and are pivoted together centrally of the U-shaped arms at 111 and each is provided with 75 a contact 112. The contact-carrying arms are

so positioned with respect to the resilient arms of the U that they will be moved to a position wherein the arms extend to one side or the other of the line passing through the pivots 113. In other words, the arms form a toggle switch.

Means for actuating the switch comprises a plunger 114, slidably mounted in the upstanding wall 96. The plunger is provided with a spring 115 surrounding the same and having one end engaging the outside surface of the wall 96, and the other end abutting a finger piece 116 secured to the outer end of the plunger to normally urge the plunger outwardly from the heating element. This outward movement is limited by a shoulder 117 formed on the plunger.

After the igniting unit has been moved to the energizing position, in which a circuit is closed through the two heating elements, the plunger is moved inwardly contacting the pivotally mounted contact arms 109 and moving them into a position as shown in Fig. 7, wherein contacts 112 engage the bimetallic element and complete the circuit to ground. As the heating elements attain their desired heat, the lens 43 on the igniting unit will glow to indicate the incandescence of the heating element and the bimetallic strip will flex and move the contact arms past the neutral position between the pivots 113, whereby the resilient arms will snap the pivoted arms into open-circuit position. With this form of the invention, once the heating element has attained its predetermined heat, the circuit cannot be remade until the switch is manually closed again.

While the two heating elements have been disclosed as being in parallel and operated by the switch, they can be placed in series if desired for coacting with a switch as is shown in Fig. 8. In this form of the invention, the switch operation is the same as described with respect to Figs. 6 and 7, however, the bimetallic thermostat 105 is secured by a strip 120 to the contact cup, whereby the circuit for the auxiliary heating element is through contact 104, central stud 99, through the heating element 97, contact cup 98, strip 120, to the thermostat 105, and through the switch, when closed, to ground.

From the foregoing, it will be seen that applicant has provided a cigar lighter with an auxiliary control which will function faithfully and which will open the circuit when the heating element attains its predetermined temperature. The control unit is so constructed that it can be readily removed for repair or replacement and several units having different modes of operation can be interchanged with the igniting unit and holder so as to satisfy the needs of the user. For example, the unit can be used in which the auxiliary heating element will be in series with the heating element on the igniting unit and the circuit closed by inserting the igniting unit to energizing position on the holder. Or, the auxiliary heating element can be placed in parallel with the heating element of the igniting unit and the circuit closed upon movement of the igniting unit into energizing position. With these two arrangements, the heating element of the igniting unit will be continually in the circuit until removed and the circuit will be closed, off and on, as the thermostat heats and cools. However, if the user desires, he can have a control unit in which the heating element can be either in series or in parallel with the heating element on the igniting unit and which is provided with a manually operable switch for closing the cir-

cuit, which switch is opened in accordance with the temperature of the auxiliary heating element and will not again close the circuit until the switch is manually actuated so that, upon the heating element attaining its predetermined heat, the circuit is opened and will not be automatically remade.

This arrangement, of course, gives the user quite a selection of operating characteristics 10 which can be had by merely selecting the proper control unit and mounting it on the holder for cooperation with the heating element on the igniting unit.

Variations and modifications may be made 15 within the scope of this invention and portions of the improvements may be used without others.

I claim:

1. In a cigar lighter, a holder; an igniting unit mounted on the holder for complete removal for 20 use; a heating element carried by the igniting unit; means for closing a circuit through the heating element upon movement of the igniting unit to energizing position; and a control unit removably mounted on the holder and connected in 25 the circuit for the first heating element, said unit comprising an auxiliary heating element, a contact carried thereby and extending into the path of the igniting unit to complete an electrical connection between the first heating element 30 and the auxiliary heating element, and heat-responsive means removably mounted on the unit and extending into heat-conducting relation with the auxiliary heating element and adapted to open the circuit when the last-named heating element 35 has attained its predetermined temperature.

2. In a cigar lighter, a holder; an igniting unit mounted on the holder for complete removal for use; a heating element carried by the igniting unit; means for closing a circuit through the 40 heating element when moved to energized position on the holder; an auxiliary heating element mounted on the holder; means for electrically connecting the heating element and the auxiliary heating element upon movement of the igniting 45 unit to energizing position; and heat-responsive switch means in the circuit and in heat-conducting relation with the auxiliary heating element for opening the circuit when the last-named heating element has attained a predetermined temperature, and manual means for completing the 50 circuit comprising a toggle switch operable to close the circuit and operatively connected with the heat-responsive means to be opened thereby when the heating element has attained its predetermined temperature.

3. In a cigar lighter, a holder; an igniting unit mounted on the holder for complete removal for use, the igniting unit having a conducting cap 60 at the inner end thereof and a heating element secured thereto; a contact in the base of the holder for engaging and closing a circuit through the heating element on the igniting unit when moved into energizing position; a heating element substantially like the first-named element 65 mounted on the exterior of the holder and provided with a contact extending into the holder for engagement with the conducting cap on the igniting unit when the igniting unit has been moved into energizing position to thus complete a circuit through both of the heating elements; and heat-responsive switch means in the circuit 70 and in heat-conducting relation with the heating element on the holder for opening the circuit when the last-named heating element has attained a predetermined temperature.

4. In a cigar lighter, a holder; an igniting unit insulatedly mounted on the holder for complete removal for use; a heating element secured to the igniting unit; contact means on the holder for connecting the heating element to a source of current; a substantially identical heating element mounted on the exterior of the holder and provided with a contact extending into the holder for engagement with the igniting unit to complete a circuit from said source of current through both heating elements upon movement of the igniting unit to energizing position; and means for opening the circuit when the last-named heating element has reached a predetermined temperature.

5. In a cigar lighter, a holder; an igniting unit insulatedly mounted on the holder for complete removal for use; a heating element secured to the igniting unit; contact means on the holder for connecting the heating element to a source of current; a substantially identical heating element mounted on the exterior of the holder and provided with a contact extending into the holder and engaging the igniting unit and electrically connecting the said two heating elements; manual means for completing the circuit from said source of current through both heating elements to a ground; and heat-responsive means in heat-

conducting relation with the heating element mounted on the holder and operatively connected with the manual means for opening the circuit when the last-named heating element has attained a predetermined temperature.

6. In a cigar lighter, a holder; an igniting unit mounted on the holder for complete removal for use; a heating element carried by the igniting unit; means for closing a circuit through the 10 heating element upon movement of the igniting unit to energizing position; and a control unit removably mounted exteriorly of the holder adapted to open the circuit through the heating element when it has attained a useful temperature 15, said unit comprising a heating element substantially identical with the first-named heating element, a contact carried thereby and extending into the path of the igniting unit to complete an electrical connection between the heating elements upon movement of the igniting unit to energizing position, and heat-responsive means in heat-conducting relation with the second-named heating element adapted to open the circuit when the latter has attained a predetermined temperature.

HERBERT G. LEHMANN.
